INVENTOR:

Leo Rosenman,

BY

Fraenkel and Richards,
ATTORNEYS

UNITED STATES PATENT OFFICE.

LEO ROSENMAN, OF NEWARK, NEW JERSEY.

FASTENER STRIP.

Application filed February 19, 1921. Serial No. 446,247.

To all whom it may concern:

Be it known that I, LEO ROSENMAN, a citizen of the United States, residing at Newark, in the county of Essex and State of New Jersey, have invented certain new and useful Improvements in Fastener Strips; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to a novel method and means of mounting hooks to strips to be used with garments; and the present invention has for its principal object to provide a novel means for attaching hooks to strips in a manner hereinafter more fully specified, and also to provide a main or base-strip which is folded in such a manner, and to which the fasteners are secured by sewing, that the line of stitching for securing the fasteners in place, is not exposed to view upon the face of the strip.

The invention has for its further object to provide a strip with an arrangement of hook or hooks, with which the latter are disposed in such a manner, that but a minimum portion of the hook or hooks is exposed to view, and still providing a positive and permanent means of fastening the hook or hooks in position.

Other objects of the present invention not at this time more particularly enumerated will be clearly understood from the following description of the present invention.

With the various objects of the present invention in view, the said invention consists, primarily, in the novel arrangements and combinations of the devices and parts, and the novel means for securing the fasteners in position upon a strip, adapted to retain the fasteners in place against movement and accidental displacement, all of which will be more fully described in the following specification, and then finally embodied in the clauses of the claims which are appended to and which form an essential part of the

said specification. The invention is fully illustrated in the accompanying drawings, in which:—

Figure 1 is a face or plan view showing a fragmentary portion of a strip or fly provided with a pair of fasteners, all arranged according to and embodying the principles of the present invention.

Figure 2 is a rear face view of the several devices illustrated in said Figure 1; and Figure 3 is a transverse vertical section taken on line 3—3 in said Figure 1.

Figure 4 is a rear face view of the strip and fasteners, showing the fasteners secured in their fixed positions by sewing, with the strip represented in its relation to said fasteners before its main body-portion is folded over upon the back of the strip in the manner illustrated in said Figure 2.

Similar characters of reference are employed in the above described views, to indicate corresponding parts.

Referring now to the several figures of the drawings, the reference-character 1 indicates what is known in the trade as the strip, the same being any desired fabric to be suitably secured to a garment. This strip, which may be of any suitable length and width, is provided at desired intervals with a series of perforations, holes or slits, as 2, suitably located near one of the longitudinally extending edge-portions of the strip, and with a second series of perforations, holes or slits, as 3, suitably located near the other longitudinally extending edge-portion of the strip, each pair of perforations, holes and slits 2 and 3, laterally across the strip or fly, being in alinement with each other, as shown in Figures 2 and 4 of the drawings.

In practice, the main body of the strip is folded longitudinally along the line of said perforations, holes or slits 2, so as to provide a flap 4, in the fold or edge 5 of which the said perforations, holes or slits 2 are thus located, as shown more particularly in said Figure 4 of the drawings. Fasteners, in the form of hooks 6 are now inserted in said perforations, holes or slits 2, in such a manner, that the eye-portions 7 thereof will be located between the said folded portions of the strip, and that the hook-portions 8 of

said fasteners will extend beyond the edge 5, in the manner indicated in said Figure 4.

The folded portion or flap 4 is now secured to the main portion of the strip by sewing in the form of a line of stitches 9, said line of stitches passing through the center of the eye-portions 7 of the fasteners 6, the straight line of stitches 9 being interrupted at the respective eye-portions 7, and 10 being angularly disposed, as at 10 and 11, said stitchings 10 and 11 being connected by intermediately disposed jump-stitches 12. It will be evident from an inspection of said Figure 4, that the various stitchings 10, 11 15 and 12 will thus securely fasten the eye-portions 7 of the fasteners 6 in place, against loose movement of the fasteners with relation to the strip, and also against any accidental displacement therefrom.

20 The said strip 1 is next folded over, in the manner illustrated in Figures 2 and 3 of the drawings, thereby forming the longitudinally extending marginal edge 13, and each hook-portion 8 of said fasteners 6 is 25 then passed into and through a perforation, hole or slit 3, so that the completed strip represented in Figure 1 will be the result, and as represented in said Figure 1, only the hook-portions 7 of the fasteners 6 30 are exposed to view, and no stitches are shown.

As shown, the strip 1 may be provided with a fold 14 for sewing the strip with its fasteners to a garment, but said fold 14 may 35 be omitted, if desired.

The strip 1 with its fasteners 6 may also be used in connection with a garment, when merely provided with but the single fold or lap, as shown in Figure 4, in which case 40 the perforations, holes or slits 3 are omitted, but I prefer to double-fold the strip, as illustrated in Figures 1, 2 and 3 of the drawings, as thereby a neater and more presentable strip is produced.

45 From an inspection of the several figures of the drawings, it will be evident that the stitchings 10 and 11 being made in directions back and forth, in the form of tack stitching, the fasteners are securely tied in place, and at the same time a re-enforcement of the sewed portions at these points takes place.

From the foregoing description of the present invention it will be seen that a 50 simple, neat and well-appearing strip for garments has been produced, and that the maximum portions of the fasteners used in

connection therewith are covered, except their working ends, so that the danger of rusting, and thereby rendering the garment 60 unsightly and unfit for wear, is reduced to a minimum; and, furthermore, the general construction is simplified because of the manner of arranging and quickly inserting the fasteners in position and sewing 65 them fast in the manner herein-above described, each fastener being retained in its operative position, against wobbling or tilting motion, as well as against displacement.

I claim:—

70 1. A fabric-strip comprising a main body-portion and a folded member in the form of a flap, the fold between said body-portion and flap being provided with an opening, a hook-shaped fastener having its main 75 portion disposed between said body-portion and said flap, and having its hook-portion extending from said opening, a line of stitching for securing said flap and fastener upon the rear face of said body-portion, 80 said stitched members being folded against the rear face of another part of said main body-portion, and a second opening laterally in alignment with said first-mentioned opening through which the hook-portion of the 85 fastener is also projected so as to extend over the outer face of the strip.

2. A fabric-strip comprising a main body-portion and a folded member in the form 90 of a flap, the fold between said body-portion and flap being provided with an opening, a fastener having eye-portions and a hook-portion, said eye-portions being disposed between said body-portion and said flap, a line of stitching for securing said 95 flap upon the rear face of said body-portion, said stitching being provided with tack-stitching and a jump-stitching passing into and about the eye-portions of said fastener, and said hook-portion extending from said 100 opening, said stitched members being folded against the rear face of another part of said main body-portion, and a second opening laterally in alignment with said 105 first-mentioned opening through which the hook-portion of the fastener is also projected so as to extend over the outer face of the strip.

In testimony, that I claim the invention set forth above I have hereunto set my hand 110 this 16th day of February, 1921.

LEO ROSENMAN.
